UNITED STATES PATENT OFFICE.

CARL G. G. BERGSTROM, OF ST. PAUL, MINNESOTA.

ATTACHMENT FOR MOTOR-VEHICLE TRANSMISSIONS

Application filed August 24, 1923. Serial No. 659,043.

To all whom it may concern:

Be it known that I, CARL G. G. BERGSTROM, a citizen of the United States, residing at St. Paul, in the county of Ramsey and State of Minnesota, have invented certain new and useful Improvements in Attachments for Motor-Vehicle Transmissions, of which the following is a specification.

My invention relates to attachments for motor vehicle transmissions and an object is to provide a device which will filter the oil used in the transmission casing. Another object is to provide a device which will insure an adequate supply of oil free from solid particles to the bands and clutch fork employed in the transmission casing.

The full objects and advantages of my invention will appear in connection with the detailed description thereof, and the novel features of my inventive idea will be particularly pointed out in the claims.

In the accompanying drawings, which illustrate one form in which my invention may be embodied,—

Fig. 1 is a longitudinal elevational sectional view of a motor vehicle transmission showing my device in place. Fig. 2 is an end view of the device detached. Fig. 3 is a view in section on the line 3—3 of Fig. 4. Fig. 4 is a central longitudinal sectional view of the device. Fig. 5 is a top plan view of the device.

Referring to the construction shown in the drawings, the numeral 10 designates the transmission casing of a motor vehicle. This casing has a covering 12. Outside of the casing are the customary brake pedal 14, clutch pedal 16 and reverse pedal 18 which operate in connection with the brake band 20, slow speed band 22, reverse band 24 and clutch fork 25 inside the casing. Also, within the casing and secured to the crank shaft is the customary fly-wheel 26, the lower portion of which runs below the surface of the oil in the casing. My device includes a dished sheet metal member having side flanges 28 provided with holes 29 for receiving the bolts which secure the cover 12 in place. The portion of the device between the side flanges is depressed as shown in Figs. 3 and 4, and the device when in place beneath the cover 12 assumes the position

shown in Figs. 1 and 4 so as to be inclined and having its upper end adjacent the upper portion of the fly-wheel 26. One of the side walls at the upper end portion is cut away to provide an opening 30 to receive the oil thrown off by the fly-wheel when rotating. The bottom of the device at its upper end portion is horizontal and is provided with an oval rib 32 within which is an opening or number of holes 34 located directly above the bands 20, 22 and 24. The lower end portion of the device is provided with a vertical enclosing wall 36 which forms a filtering chamber open at top and bottom. The upper edge of the wall 36 is connected with the horizontal floor portion by an inclined floor portion 38. The lower edge of the wall 36 is provided with an internal annular flange 40 upon which rests a perforated disc 42 upon which is placed a mass of suitable filtering material 44 on the top of which is a second perforated disc 46 held in place by a resilient split ring 48.

The operation and advantages of my invention will now be obvious. Oil thrown off by the fly-wheel 26 passes through the opening 30, drops upon the floor of the device and runs down to the filter which retains the solid particles of grit and dirt carried by the oil. The filtered oil drops from the lower end of the filtering chamber upon the clutch fork 25. Oil accumulates at the top of the filtering chamber faster than it can run through and backs up on an inclined bottom 38 and over the rib 32 so as to drop on the bands 20, 22 and 24. The provision of the oval rib 32 prevents most of the oil which is thrown by the fly-wheel upon the horizontal floor portion from reaching the bands until it is first gravitated to the filter, so that the solid particles are separated out of the oil.

I claim:

1. An attachment for motor vehicle transmissions comprising a dished member for catching oil thrown off from the fly wheel, said member having an inclined floor portion, a filter at the lower end of said inclined portion located above the clutch fork, the upper portion of the floor of said member having an opening positioned above the bands of the transmission, and means for preventing particles of grit from passing to said opening.

2. An attachment for motor vehicle transmissions comprising a dished sheet metal member for catching oil thrown off from the fly-wheel, said member having a horizontal floor and an inclined floor leading from said horizontal floor, a filter at the lower end of said inclined floor adapted to deliver oil to

the clutch fork, and a longitudinally extending oval rib on said horizontal floor surrounding an opening which is adapted to deliver oil to the bands of the transmission. ¹⁰

In testimony whereof I hereunto affix my signature.

CARL G. G. BERGSTROM.
